ATTORNEYS

UNITED STATES PATENT OFFICE.

OLIVER PERRY SCOTT, OF TACOMA, WASHINGTON.

ELECTRIC HEATER.

1,401,500.

Specification of Letters Patent. Patented Dec. 27, 1921.

Application filed October 17, 1919, Serial No. 331,336. Renewed August 4, 1921. Serial No. 489,901.

To all whom it may concern:

Be it known that I, OLIVER PERRY SCOTT, a citizen of the United States, and a resident of Tacoma, in the county of Pierce and State of Washington, have invented certain new and useful Improvements in Electric Heaters, of which the following is a specification.

My invention relates to electric heaters adapted for the heating of air or water, and a purpose of my invention is the provision of an electric heater of simple and substantial construction, wherein the elements comprised in the heater are exposed to facilitate the repairing thereof.

It is also the purpose of my invention to provide an electric heater which consumes a minimum quantity of current, the construction of the heater being such that it may be used either for heating water or air.

I will describe two forms of electric heaters embodying my invention and will then point out the novel features in the claim.

In the accompanying drawings:—

Figure 1 is a view showing a flue of a hot air heating system having applied thereto one form of electric heater embodying my invention;

Fig. 2 is a view showing in side elevation and partly in section the heater shown in Fig. 1;

Fig. 3 is an end elevation of Fig. 2;

Fig. 4 is a view showing a hot water tank having applied to the feed pipe thereof another form of electric heater embodying my invention;

Fig. 5 is a longitudinal sectional view of the heater shown in Fig. 4; and

Fig. 6 is a transverse sectional view of Fig. 5.

Referring specifically to the drawings, and particularly to Fig. 2, the first form of electric heater embodying my invention comprises a tube T formed of insulating material such as clay, porcelain, concrete or the like and having coiled spirally thereabout an electric heating unit H. The heating unit H consists of a single length of conducting wire which is coiled upon itself and secured at its opposite ends to the tube T by means of binding posts P. The binding posts P extend through the wall of the tube T and form an attaching means for conducting wires W which supply current to the heating unit to thereby heat the lat-

ter substantially to a point of incandescence. In the practical application of the electric heater, the heating unit H is formed of relatively thick wire so that when current traverses the same it will not be heated to the point of incandescence but to a dull red heat. This reduces the liability of the wire becoming unduly heated and burning out thereby prolonging its life.

In Fig. 1, I have shown the electric heater just described in applied position within a flue F of a hot-air heating system. B designates the boiler of this heating system which supplies hot air to a room through the medium of the flue F, the passage of hot air through the flue being controlled by a damper D. The electric heater is supported within the flue F by means of brackets 15 and 16 which are secured to the walls of the flue and to the opposite ends of the tube T so that the heater is disposed longitudinally of the flue. When the heating system is not in use, hot-air may be supplied to a room by means of the electric heater, it being understood that when the draft D is opened a current of air is created within the flue F by the heat generated from the heating unit H.

Referring now to Figs. 5 and 6, I have herein shown another form of electric heater embodying my invention, wherein T' designates a tubular support formed of insulating material and about which a heating unit H' is coiled. The heating unit H' is the same as the heating unit H in the other form of my invention and is secured at its opposite ends to the support by binding posts P. As illustrated to advantage in Fig. 6, the support T' is in the form of a Pattée cross in section to provide longitudinally extending ribs 17, which are co-extensive in length with the support. As shown in Fig. 5, the heating unit H' is coiled about and supported by the ribs 17 so that practically the entire surface of the heating unit is exposed and free to radiate the heat. At the opposite ends of the support T', circular heads 18 are provided which are formed at spaced intervals with transversely extending openings 19 for the purpose of admitting air to the heating unit H'. Surrounding the support T' and bearing against the heads 18 is a metallic casing 20, while surrounding the latter is an asbestos covering 21. It will be understood that the metallic casing 20 forms

a rigid support for the asbestos cover 21, while the latter serves to prevent radiation of heat from the heating unit H'.

Referring now to Fig. 4, I have herein shown a hot water tank A to which water is supplied by means of a pipe K. In the applied position of the second form of heater the tubular support T' snugly receives the pipe K, as illustrated to advantage in Figs. 10 5 and 6.

When current is supplied to the heating unit H' the heat generated by the current is transmitted to the pipe K thereby effectively heating the water as it is supplied to the 15 tank A. In Fig. 4, I have shown the asbestos covering 21 extended beyond the support T' so as to cover a major portion of the pipe K. The covering 21 is supported in proper position with respect to the pipe K by means 20 of brackets 22 and 23 which are in turn supported by the tank A.

Although I have herein shown and de-

scribed two forms of electric heaters and two methods of heating, it is to be understood that various changes and modifications 25 may be made without departing from the spirit of the invention and the spirit and scope of the appended claim.

Having thus described my invention, I claim:

An electric heater comprising a tube formed of insulating material, longitudinally extending ribs formed exteriorly of said tube, circular heads formed on the opposite ends of said tube and having perforations formed therein, a heating unit arranged about said tube and engaging said ribs, a metallic casing surrounding said tube and supported upon said heads in a manner to dispose a major portion of the casing in 40 spaced relation to the tube, and heat insulating material surrounding said casing.

OLIVER PERRY SCOTT.
